ROLLING-MILL OR SIMILAR INSTALLATION.

1,109,885.

Specification of Letters Patent.

Patented Sept. 8, 1914.

Application filed March 11, 1913. Serial No. 753,622.

To all whom it may concern:

Be it known that I, WILLIAM R. WEBSTER, a citizen of the United States, residing in Bridgeport, county of Fairfield, and State of Connecticut, have invented certain new and useful Improvements in Rolling-Mill or Similar Installations, of which the following is a full, clear, and exact description.

This invention relates to metal working devices for operating on strips, bars, wires or other lengths of stock. The improvements are especially intended for application to metal working devices arranged in tandem for simultaneous operation upon successive portions of a length of stock fed from one of such devices to another of the same, but certain features of the invention may be used to advantage in other connections.

I shall describe the invention as applied to a rolling mill installation but it will be apparent that in the broader aspects of the invention, the character of the metal working device or devices and of the stock operated on thereby may be considerably varied.

The cold rolling of flexible metal strips has heretofore generally been confined to the use of one rolling mill through which the strip is passed to reduce its thickness, and from which the strip passes directly to the winding drum. There have recently been some attempts to roll these strips by passing them through two or more individually driven sets of rolls placed in tandem with each other, but this tandem rolling has been unsatisfactory owing to the impossibility of properly controlling the speeds of the respective mills. In this method of rolling it is necessary, in order to obtain satisfactory results, to control the relative speeds of the mills in such a manner that variations of speed of one mill, (due to external causes or to hard spots in the metal or expansion of the rolls) will be compensated for by variations of speed of the other mill or mills. Where the speed of the mills is regulated by the operative by means of manual controlling devices associated with the prime movers of the respective mills, it is practically impossible to meet the condition, and as a result, the distribution of the work of reduction between the mills is very uneven, the tension of the stock passing from one mill

to another fluctuates considerably, and the results of the operation as a whole are generally unsatisfactory.

One of the primary objects of the present invention, therefore, is to provide improved means for regulating automatically the relative speeds of two or more rolling mills or other metal working devices arranged in tandem so as to maintain a practically uniform tension in the stock between the mills. More particularly, I aim to provide an installation in which one of the rolling mills or other metal working devices is movable toward and away from the other by variations in the tension of the stock, and wherein this movement is utilized to control automatically the speed of a prime mover which drives one of the mills. It is also proposed to furnish a metal working device which is bodily movable on its foundation and so arranged with respect to a speed controlling device for a prime mover, that the speed of said prime mover will be varied in accordance with the tension of the stock acted on by said metal working device.

To these and other ends, the invention consists in the novel features and combinations of parts to be hereinafter described and claimed.

In the accompanying drawings, Figure 1 is a diagrammatic side elevation of a rolling mill installation embodying my invention, Fig. 2 is a similar view showing the movable mill in another position, Fig. 3 is a top plan view of Fig. 1, and Fig. 4 is an end view of Fig. 1.

The rolling mill installation shown in the drawings, comprises a mill A and a mill B, individually driven and arranged in tandem for simultaneous operation upon a length of stock C such as a strip of brass or other metal. The strip to be reduced passes from a holder D to the mill A, thence to the mill B and finally to a winder E. The mill A comprises a stand 5 having the usual rolls 6, 7 operated by an electric motor 8 through the customary reducing gearing. Similarly, the mill B comprises a stand 9 having rolls 10, 11, and an electric motor 12 for driving said rolls.

In the embodiment illustrated, the mill A, which may be termed the first mill, is movable bodily toward and away from the mill

B. The roll stand 9 of the mill B is fixed on a foundation F, but the roll stand 5 of the mill A is mounted on a movable platform 13 adapted to travel toward and away from the mill B on a track 14 carried by the foundation G. The particular movable mounting of the platform 13 or its equivalent is not a material feature of the invention but in the case illustrated said platform 10 is equipped with wheels 15 and the track 14 is constituted by parallel rails for said wheels.

The movable mill A is acted on by means urging it away from the mill B and tending 15 to hold the platform 13 against stops 16. This means may comprise a fluid pressure device H fixed on the foundation F and constituted by a cylinder 17 and a piston 18 which is subjected to the force of a pressure 20 medium entering the cylinder 17 by way of an inlet pipe 19. The piston 18 is rigidly connected with the platform 13 by means of the piston rod 20, and the mill A is constantly urged toward the stops 16 by constant connection of the pressure cylinder 17 25 with a suitable source of pressure medium. The stops 16 limit the movement of the mill A away from the mill B and similar stops 21 limit the movement of the mill A toward 30 the mill B.

The motor 8 of the mill A has associated with it a rheostat 22 whereby the speed of the motor is controlled. The rheostat 22 may be conveniently located on the foundation 35 G alongside the track 14. It is operated by a controller handle 23 having a fixed pivot 24 and coöperating with the rheostat in the usual manner. The upper free end of the controller handle 23 is pivoted at 25 to one end of a link 26, the opposite end of which is pivoted at 27 to a part of the mill A, such as one of the side frames of the roll stand 5.

The operation of the installation is substantially as follows: The strip of metal to 45 be reduced is passed from the holder D through the rolls 6 and 7 of the mill A and thence through the rolls 10 and 11 of the mill B. When the mills have been started 50 the mill A will normally have a position about midway of the length of its track or guideway in which position the portion of the stock between said mill and the mill B, will be subjected to just the right amount of 55 tension for the efficient operation of the mills, the work of reduction being suitably divided between the mill A and the mill B. Under these normal conditions the tension in the stock between the mills is equal to 60 the pressure on the piston or plunger 18. Should this tension increase, due to any inequality in the rolling mill operation or to external causes (such as voltage fluctuations) the force exerted by the device H 65 on the mill A will be overcome and the ten-

sion of the stock will be sufficient to pull the mill A toward the mill B. In doing this the controller handle 23 of the rheostat 22 will be swung on its pivot in an obvious manner, and the arrangement is such that this movement of the controller handle will act to speed up the motor 8. Hence the mill A will feed in the metal faster than before, and this will eliminate at once the undue tension in the stock, such tension being decreased 75 until it equals that of the balancing means H. On the other hand, if the tension in the stock decreases below the pushing effect of the balancing means H, the latter will act to move the mill A farther away 80 from the mill B. A movement of the mill A in this last named direction will obviously move the controller handle 23 in a direction opposite to that first mentioned and as a consequence the speed of the motor 8 will be decreased until the equilibrium between 85 the pressure of the balancing means and the tension of the stock is again restored. It will therefore be understood that both increases and decreases of tension in the stock 90 between the mills, above and below respectively the normal, are quickly eliminated in an automatic manner so that for all practical purposes a constant tension in the intermediate portion of the stock is automatically maintained.

As soon as a length of stock leaves the mill A the device H will move said mill against the stops 16 and the mill will operate at a greatly reduced speed as long as it 100 is idle. As soon as a new length of stock is fed into the mill A and thence into the mill B, the relative speeds of the two sets of 105 rolls is such that the mill B will rapidly take up any slackness in the stock between the mills and will begin to draw the mill A toward the mill B. This continues until the mill A has speeded up sufficiently to decrease the tension of the stock between the 110 mills and equalize it with the power of the balancing means H, which will occur when the mill A reaches a position about midway of the track 14.

Of course, the character of prime mover employed and the speed controlling device 115 therefore is immaterial so far as the general principles of the invention are concerned. Moreover, it is not essential to employ a fluid pressure device for balancing the movable mill, nor to support the latter by means of wheels or rollers. In the form shown, both devices A and B reduce as well as support the stock, but the reducing function of either A or B may be omitted in some cases. Many modifications in these and other respects may be adopted without departing 120 from the scope of my invention as defined in the claims.

What I claim is:

1. The combination of a metal working 130

device adapted to act on a length of stock, a device spaced from said metal working device and supporting the stock acted on by the latter, one of said devices being movable toward and away from the other, a prime mover for driving one of said devices, and a speed adjusting means for said prime mover controlled automatically by the bodily movements of said movable device; substantially as described.

2. The combination of a metal working device adapted to act on a length of stock, a device spaced from said metal working device and supporting the stock acted on by the latter, a track on which one of said devices is movable toward and away from the other, a prime mover for driving one of said devices, and a speed adjusting means for said prime mover controlled automatically by the bodily movements of said movable device; substantially as described.

3. The combination of a metal working device adapted to act on a length of stock, a device spaced from said metal working device and supporting the stock acted on by the latter, a track on which one of said devices is movable toward and away from the other, separate prime movers for the respective devices, and speed adjusting means for one of said prime movers controlled automatically by the bodily movements of said movable device; substantially as described.

4. The combination of a metal working device adapted to act on a length of stock, a device spaced from said metal working device and supporting the stock acted on by the latter, one of said devices being movable toward and away from the other, balancing means acting on the movable device, a prime mover for driving one of said devices, and speed adjusting means for said prime mover operatively connected with said movable device; substantially as described.

5. The combination of a power driven metal working device adapted to act on a length of stock, a power driven device spaced from said metal working device and supporting the stock acted on by the latter, one of said devices being movable toward and away from the other, and means for varying the working speed of one of said devices in consonance with the bodily movements of said movable device; substantially as described.

6. The combination of a power driven metal working device adapted to act on a length of stock, a power driven device spaced from said metal working device and supporting the stock acted on by the latter, one of said devices being movable relatively to the other, and means to decrease the working speed of one of said devices as the distance between said devices is in-

creased and to increase such speed as the distance between said devices is decreased; substantially as described.

7. The combination of a metal working device adapted to act on a length of stock, a device spaced from said metal working device and supporting the stock acted on by the latter, one of said devices being movable toward and away from the other, balancing means acting on the movable device, a prime mover for one of said devices, and means for increasing the speed of said prime mover as the distance between said devices is decreased and vice versa; substantially as described.

8. The combination of a metal working device adapted to act on a length of stock, a device spaced from said metal working device and supporting the stock emerging from the latter, a track on which one of said devices is movable toward and away from the other, balancing means acting on the movable device, separate prime movers for the respective devices, and speed adjusting means for one of said prime movers which speeds up said prime mover automatically as the distance between said devices is decreased and slows down said prime mover as the distance between said devices is increased; substantially as described.

9. The combination with a suitable foundation, of a bodily movable power driven metal working device mounted thereon and adapted to operate on a length of stock, and means to vary the working speed of said device automatically as the same moves relatively to said foundation; substantially as described.

10. The combination with a suitable foundation, of a bodily movable power driven metal working device mounted thereon and adapted to operate on a length of stock, means spaced from said device to support the stock acted on by the latter, and means to vary the working speed of said device automatically as the same moves relatively to said foundation; substantially as described.

11. The combination with a track, of a bodily movable power driven metal working device thereon and adapted to operate on a length of stock, and means to vary the working speed of said device automatically as the same moves along said track; substantially as described.

12. The combination of metal working devices arranged in tandem, one of said devices being movable toward and away from the other, and means for automatically varying the working speed of one of said devices in consonance with the bodily movements of said movable device; substantially as described.

13. The combination of metal working devices arranged in tandem, one of said de-

vices being movable toward and away from the other, separate prime movers for the respective devices, and speed adjusting means for one of said prime movers controlled automatically as the tension in the stock between said devices is varied; substantially as described.

14. The combination of metal working devices arranged in tandem to act simultaneously on successive portions of an advancing length of stock, one of said devices being bodily movable toward and away from the other, prime movers for the respective devices, and a speed adjusting means for one of said prime movers actuated automatically to increase the speed as said movable device approaches the other device and to decrease the speed as said movable device moves in the opposite direction; substantially as described.

15. The combination of metal working devices arranged in tandem for simultaneous operation on successive portions of an advancing length of stock fed from one of said devices to the other, the device which first receives the stock being movable toward and away from the second device, prime movers for the respective devices, and speed adjusting means for the prime mover of the first device actuated automatically to increase the speed of said prime mover as said first device moves toward the second and to decrease the speed as said first device moves away from the second; substantially as described.

16. The combination of metal working devices arranged in tandem, prime movers for the respective devices, a track on which one of said devices is movable toward and away from the other, means normally holding said movable device in a definite position lengthwise of said track, and speed adjusting means for one of said prime movers controlled automatically by the bodily movement of said movable device lengthwise of said track; substantially as described.

17. The combination of rolling mills arranged in tandem, one of said mills being movable toward and away from the other, and means for automatically varying the rolling speed of one of said mills in consonance with the bodily movement of said movable mill; substantially as described.

18. The combination of rolling mills arranged in tandem, one of said mills being movable toward and away from the other, separate prime movers for the respective mills, and speed adjusting means for one of said prime movers controlled automatically as the tension in the stock between the mills is varied; substantially as described.

19. The combination of rolling mills arranged in tandem, the first mill being movable toward and away from the second mill, prime movers for driving said mills sepa-

rately, and speed adjusting means for one of said prime movers controlled automatically by the bodily movements of said first mill; substantially as described.

20. The combination of rolling mills arranged in tandem, the first mill being movable bodily toward and away from the second, prime movers for driving the respective mills separately, and means for varying automatically the speed of the prime mover of said first mill as the latter changes its position relatively to the second mill; substantially as described.

21. The combination of rolling mills arranged in tandem, one of said mills being bodily movable toward and away from the other, prime movers for the respective mills, balancing means acting on the movable mill, a speed regulating device for one of said prime movers, and an operative connection between said speed regulating device and said movable mill; substantially as described.

22. The combination of a metal working device, a track on which said device is bodily movable, a prime mover for driving said device, a speed regulating device for said prime mover, and a connection between said speed regulating device and said metal working device whereby the speed of the latter is varied automatically; substantially as described.

23. The combination of a foundation having a track, a rolling mill movable bodily on said track, a prime mover for driving said mill, a speed regulating device for said prime mover, and automatic means for adjusting said speed regulating device as the mill varies its position on said track; substantially as described.

24. The combination of a foundation having a track, a rolling mill bodily movable on said track, balancing means acting on said mill to hold it normally in a definite position lengthwise of the track, a prime mover for driving said mill, a speed regulating device for said prime mover, and means to adjust said speed regulating device automatically as said mill moves to and fro on said track; substantially as described.

25. The combination of rolling mills arranged in tandem, one of said mills being movable toward and away from the other, an electric motor for driving one of said mills, a rheostat for controlling the speed of said motor, and an operative connection between said rheostat and said movable mill whereby the speed of said prime mover is increased as the movable mill approaches the fixed mill; substantially as described.

26. The combination of a track, a rolling mill movable bodily on said track, an electric motor for driving said mill, a rheostat for said motor, and means for operating said rheostat automatically as the mill moves along the track; substantially as described.

27. The combination of a track, a platform movable along said track, a metal working device on said platform, an electric motor for said device likewise mounted on said platform, a rheostat for said motor fixed relatively to said track, and operative means of connection between said metal working device and said rheostat; substantially as described.
- 10 28. The combination of rolling mills arranged in tandem, a platform on which one of said mills is supported, a track on which
- said platform is movable, an electric motor for the movable mill, carried by said platform, and means to increase the speed of 15 said motor automatically as the movable mill approaches the fixed mill; substantially as described.
- In witness whereof, I have hereunto set my hand on the 6th day of March, 1913.

WILLIAM R. WEBSTER.
